LIGHT DIFFUSION FIXTURE

Sam Kramer, Elizabeth, N. J., assignor to Beaux Arts Lighting Co., Inc., New York, N. Y., a corporation of New York

Application June 16, 1936, Serial No. 85,450

1 Claim. (Cl. 240—78)

My present invention relates to illuminating devices, and more particularly to electrical illuminating fixtures of the light diffusion type.

In the past it has been proposed to employ 5 louvers as light diffusion devices in electrical illuminating fixtures of the suspended type. This prior louver construction has not, however, taken into account such factors as design harmony with the remainder of the fixture; variability of degree 10 of diffusion; simplicity and economy of fabrication and installation. In other words, light diffusion louvers of the past have been provided with the sole purpose of minimizing glare from electrical illuminating fixtures of the 15 ceiling suspended type; this being usually accomplished by disposing the louver elements, constructed of metal, across the illuminating opening of the fixture bowl. This resulted in directing attention to the fact that the fixture bowl included a metallic element, and detracted from 20 the general design harmony. Again, the geometric treatment of the louver design did not lend itself to any adjustment of the degree of light diffusion, should such be the desire of the 25 fixture user.

It may, therefore, be stated that it is one of the main objects of my present invention to provide in an electrical illuminating fixture, of the type ordinarily suspended from a ceiling, a light-diffusing, metallic louver which is of such geometrical configuration, and so treated on its illuminated surface, as to simulate the appearance of glass whereby the metallic louver can be used in association with a glass light bowl with- 30 out interference with the design harmony of the fixture.

Another important object of the invention is to provide a light diffusion louver, for use in ceiling type illuminating fixtures employing direct illumination, which louver consists of a plurality of concentrically-arranged, metallic, conical frustums, means being provided to rigidly relate the frustums in such a manner that when illuminated they act to diffuse the light on one side 40 thereof, and concentrate the light on the other side; and the surfaces of the frustums being treated in such a manner that the illumination thereof creates an illusion to a person viewing the fixture that the louver is fabricated from 45 glass.

Still other objects of the invention are to improve generally the simplicity, efficiency and appearance of electrical illuminating fixtures, and more especially to provide such fixtures in an economical manner.

The novel features which I believe to be characteristic of my invention are set forth in particularity in the appended claim; the invention itself, however, as to both its construction and method of operation will best be understood by 5 reference to the following description taken in connection with the drawing in which I have indicated diagrammatically a construction whereby my invention may be carried into effect.

In the drawing:
Fig. 1 is a front view of a light fixture embodying the invention,

Fig. 2 is a bottom view of the fixture, and
Fig. 3 is a partial section taken along line 3—3 15 of Fig. 2 looking in the direction of the arrows, showing the louver details viewed as in Fig. 1.

Referring now to the drawing, wherein like reference characters in the different figures designate similar elements, there is shown in Fig. 1 a type of lighting fixture generally well known 20 in the prior art; it comprises an element 1 customarily secured to the ceiling, or other support surface, from which the fixture is to be suspended. The usual hollow tube 2 depends from base 1, the latter also being hollow; and bowl support 25 3 is adjustably secured to the tube 2. The illumination bowl 4 is of the well known type, and is fabricated from translucent glass whereby the light from the bulb 5 (shown in dotted lines) within the bowl is prevented from directly illuminating any of the objects in its vicinity. The frosted, or opalescent, quality of the glass bowl 4 accounts for this; light from bulb 5 can reach 30 objects only indirectly by transmission through the walls and top of the bowl, or by reflection from 35 the surfaces of the conical frustums of the light diffusion louver 6.

The bowl 4 is rigidly secured to support 3 in the known manner; the threaded bolts 7 are used to secure the usual curled rim of the circular 40 opening in the bowl top to the support. The bulb 5 is screwed into socket 8 as is conventional; the upper portion 8' of the support 3 can be made hollow to telescope with socket 8. Threaded securing means 9, 9' are then employed to adjust 45 the spacing between the bulb 5 and the louver 6. Of course, the electrical wiring to the socket 8 is run through base 1 and tube 2. By this construction it is possible to adjust the degree of light diffusion caused by louver 6. In assembling 50 the fixture, the support 3 is secured to socket 8, the bulb 5 being screwed in operative position; the bowl, and associated louver, is then attached to support 3 by adjusting bolts 7. It is believed that a sufficient description has been given con- 55

cerning the general construction of the entire fixture.

The louver 6, as shown in detail in Figs. 2 and 3, consists of a plurality of metallic bands 10, 11, 12 and 13; each band having the shape of the frustum of a cone. These bands are concentrically arranged with respect to a common axis passing through the vertical line of intersection of positioning strips 14 and 15. The outer band 13 is provided with a circular flange 16. By means of the flange the louver assembly is rigidly secured to the bowl rim 4'; a plurality of spaced clamps 17 being attached to the flange 16 for this purpose.

Each clamp 17 consists of a rectangular strip of metal; a portion 17' of which, of a length equal to the width of flange 16, is affixed to the upper surface of the flange as by soldering, or in any other well known manner. When the remainder of a strip 17 is bent into clamping position it operates with the portion 17' to tightly clamp the rim 4' between portion 17' and upper portion 18. Accordingly, each clamp strip 17 should be given a length sufficient to firmly grip the rim 4' when the strip is in operative position. Four such clamp strips are shown spaced at ninety degree distances; but the number of such clamp strips; manner of spacing; and mode of bending into clamping position are all subject to variation, and dependent on the size of the louver.

When the frustums are in proper relation the upper rims thereof are in a common plane; substantially the entire body of the band 13 being disposed within the interior of bowl 4, and only the flange 16 being exposed. In other words, the louver 6 is positioned within the circular opening in the bowl bottom face by virtue of the attachment between the flange 16 and the periphery of the aforesaid opening. The bands 12, 11 and 10 are arranged in overlapping relation; as shown in Fig. 3 in detail, the extent of projection of each of the bands from each next preceding band is substantially the same. Further, the flare of each frustum differs; that of band 10 being relatively slight in comparison to the others. The degree of flare increases from the inner frustum to the outer one. As shown in Fig. 1, the three inner bands 12, 11 and 10 extend beyond flange 16 distances such that a pleasing design results.

The frustums are secured together in the spaced relation shown by means of strips 14 and 15. These strips are arranged at right angles, each strip being provided with a slot at its mid-point; each slot extending only about half way across a strip. Thus, the mid-portion of strip 15 is disposed in the slot 14' of strip 14. In this way the top and bottom edges of the strips are respectively in the same planes. The contacting portions of the strips are soldered to each other thereby providing a secure joint at the line of intersection of the strips.

The strips 14 and 15 are rigidly secured to the concentric bands by providing slots 20 in the latter to receive the strips in vertical position. As shown in Fig. 2, each band is provided with four spaced slots 20; these slots are aligned to receive the intersecting strips 14, 15. The strips 14, 15 and slots 20 are soldered at the points of contact thereof; this provides a rigid louver assembly. It will be noted that the strips 14 and 15, when the louver is in assembled position, are located within

bowl 4, and cannot be seen by an observer looking at the fixture.

The surfaces of the louver elements are sprayed with a material providing a silvery lustre. Preferably this is a dull lustre. For example, a mixture of aluminum powder in lacquer, brought to air gun-spraying consistency, can be used for this purpose. When so treated the exposed illuminated surfaces of the louver create a distinct illusion that the latter is constructed of glass. This may be explained by the fact that the light from bulb 5 directly falls on the outer faces of the frustums; and the inner faces of the latter receive light by reflection from the adjacent outer frustum faces. The inner face of frustum 10, of course, receives light directly from bulb 5. Accordingly, it will be seen that the conical configuration of the bands, as well as the silvery lustre, cause the observer to think he is looking at a glass louver since light appears to be passing through the bands themselves. This configuration, at the same time, produces a wide diffusion of light; the pattern of distribution is roughly a cone. Glare, of course, is eliminated by the overlapping action of the louver bands.

The advantages of this novel construction will now be clear. The bowl 4 and louver 6 both appear as a one piece glass construction when the bulb 5 is operative. This greatly enhances the design value of the fixture, and gives a wider market to a glass-metal fixture. By virtue of the louver construction, and its conical light distribution zone, adjustment of the louver with respect to the bulb 5 will cause a change in the light intensity. As the bowl is raised, for example, the light intensity emitted through louver 6 is reduced. This adjustment is desirable for many purposes. Hence, the present louver construction has a threefold function: it simulates glass when illuminated making it feasible to use a glass bowl; it makes possible degree of illumination adjustment; and reduction of glare is accomplished even though direct lighting is employed.

While I have indicated and described a system for carrying my invention into effect, it will be apparent to one skilled in the art that my invention is by no means limited to the particular construction shown and described, but that many modifications may be made without departing from the scope of my invention, as set forth in the appended claim.

What I claim is:

In an electrical illuminating fixture of the type ordinarily suspended from the ceiling, and which fixture employs a glass bowl housing an electrical bulb, said bowl being provided with an opening in the bottom thereof, a metallic louver comprising a plurality of bands each having the shape of a conical frustum, means rigidly maintaining the bands in concentric relation about a common axis, means securing the outer band to the rim of the bowl opening, the bands projecting progressively greater distances from the bowl opening from the outermost band to the innermost band, all the surfaces of said bands being coated with a material imparting a dull silvery lustre thereto, and the bands being outwardly flared whereby illumination of the coated surfaces causes the exposed surfaces of the bands to simulate glass.

SAM KRAMER. 70
